US0D1031548S

(12) **United States Design Patent** (10) **Patent No.:** **US D1,031,548 S**
(45) **Date of Patent:** **** Jun. 18, 2024**

(54) **CONTROLLER WITH MOTOR FOR POWER STEERING**

(71) Applicant: **NSK Ltd.**, Tokyo (JP)

(72) Inventor: **Kazuhiro Ohira**, Tokyo (JP)

(73) Assignee: **NSK LTD.**, Tokyo (JP)

(**) Term: **15 Years**

(21) Appl. No.: **29/791,741**

(22) Filed: **Feb. 3, 2022**

(30) **Foreign Application Priority Data**

Nov. 22, 2021 (JP) ..... 2021-025528 D

(51) **LOC (14) Cl.** **12-16**

(52) **U.S. Cl.**

USPC **D12/177**

(57) **CLAIM**

The ornamental design for a controller with motor for power steering, as shown and described.

DESCRIPTION

FIG. 1 is a front, top and right-side perspective view of showing my new design;

FIG. 2 is a rear, bottom and left-side perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof; and,

FIG. 8 is a bottom plan view thereof.

1 Claim, 8 Drawing Sheets
